UNITED STATES PATENT OFFICE.

ANDREW SHOGREN, OF AURORA, ILLINOIS.

COMBINED STEAM-HEATING AND VENTILATING APPARATUS.

SPECIFICATION forming part of Letters Patent No. 350,949, dated October 19, 1886.

Application filed November 28, 1885. Serial No. 184,189. (No model.)

To all whom it may concern:

Be it known that I, ANDREW SHOGREN, residing at Aurora, Illinois, have invented certain new and useful Improvement in a Combined Steam-Heating and Ventilating Apparatus, of which the following is a specification.

My invention relates to a combined heating and ventilating apparatus, and has for its object to provide simple, economical, and effective means for supplying buildings with steam heat and pure warm air for ventilating purposes.

In the accompanying drawings, Figure 1 is a central vertical section of my improved heating apparatus, and Fig. 2 is a longitudinal section of the same.

The apparatus illustrated in the drawings has an upright tubular boiler, a central fuel-magazine, A, the latter having an adjustable extension, a, terminating within a tapering fire-pot, B, below which is the ash-pit. This fuel-magazine A extends above the boiler and through the top plates, hereinafter described, and has a cover, a', which is removed when the magazine is to be filled. The fire-pot rests upon an elevated portion, c, of a base-plate, C, and the latter has flanges c' c', which receive the lower ends, respectively, of two jackets which inclose the boiler. A second circular plate, D, surrounds the shell of the boiler and closes the space between the latter and the jacket I, forming with the latter and the base-plate C an annular smoke-chamber, E. A flue, E', leads from the back of this smoke-chamber to a smoke-pipe at the rear. A series of direct flues, F, proceed from the top of the fire-pot up through the steam-space and open into an annular smoke-chamber, G. Proceeding downward from this chamber is a series of return-flues, H, which pass down through the water-space of the boiler and open into the smoke-chamber E. The top of smoke-chamber G is formed by a cap, G', surrounding the fuel-magazine and having a projecting flanged rim, g. The cap G' has openings corresponding in position and number to the flues to permit access to them for cleaning. These openings are covered by a removable top plate or cover, g', except when the flues are being cleaned. A jacket, I, incloses the boiler, its lower end resting on base-plate D, and its upper end resting against the under side of the rim g. The jacket I, the base-plate D, the rim g, and the

outer shell of the boiler form a heat-reservoir, which has direct communication with the fire-pot through transverse flues M M. In operation this reservoir will become filled with the products of combustion, and to insure the passage of the products of combustion from the fire-pot into this chamber the plate D may be loosely fitted, so as to maintain a limited draft from the fire-pot through this chamber or heat-reservoir and into the smoke-chamber E, thus heating said chamber by direct heat. It will be understood, however, that the principal portion of the products of combustion pass up the flues F. A second jacket, J, surrounds the first, its lower end resting on base-plate C, and the space between its upper end and the jacket I is closed by means of a removable cap or cover, j, which surrounds the upper end of the fuel-magazine. Air-pipes K lead from the upper end of this chamber to conduct the warmed air to the rooms to be ventilated. Fresh atmospheric air is admitted to the space between the jackets by a pipe, k.

To prevent the cold air rising immediately on entering its chamber, and to cause it to circulate around the warm-air chamber, I provide a flange, L, which closes the space between the two jackets at a point about half way up their sides, and extends about half-way around, as shown in Fig. 2. The jacket J is provided with a door opening opposite the front flue, M, through which access is had to the fire-pot for putting in kindling or soft coal.

To prevent dropping of the coal, &c., into the chambers I provide a trough, N, which extends from the outer jacket to the boiler-shell. A direct-draft flue, O, opens at one end into the chamber G, and at the other into the smoke-pipe P at the rear. This flue O and pipe P are provided with suitable dampers, o p. A steam-pipe, S, communicates with the steam-space of the boiler. It will be understood that this steam-pipe is designed to communicate with steam-coils in the apartment to be warmed, and that the hot-air pipes from the ventilator-chamber are designed to communicate with suitable registers in the same apartment for ventilating purposes.

It is apparent that the ventilator-chamber may be employed as a cold-air ventilator in warm weather when no steam is generated.

By my construction and arrangement means

for securing warm air for ventilating purposes are combined with a steam-boiler designed to furnish steam heat in a simple and convenient manner, and the employment of the heat-reservoir results in an appreciable economy of fuel, prevents the cooling of the shell of the boiler by the cold air in the outer chamber, and provides for heating this air.

I am aware that combined steam-heating and air-warming apparatuses are old, and therefore do not claim such, broadly.

What I claim as new, and desire to secure by Letters Patent, is—

In a steam-heating and ventilating appa-

ratus, the combination of an upright tubular boiler having a central fuel-magazine and fire-pot and suitable smoke-passages, an inner surrounding jacket forming with said boiler a heat-reservoir, a transverse flue or flues communicating with said reservoir and said fire-pot, and an outer surrounding jacket provided with an opening to admit atmospheric air, and outlet-pipes for said air when heated, substantially as described.

ANDREW SHOGREN.
